METHOD OF MAKING A GOLF BALL

Charles W. Leguillon, Akron, Ohio, assignor to
The B. F. Goodrich Company, New York, N. Y.,
a corporation of New York

Application November 10, 1934, Serial No. 752,453

1 Claim. (Cl. 154—18)

This invention relates to balls, such as golf balls, having as component parts an inner envelope containing a liquid, semi-liquid or mobile substance, a tense winding of rubber thread thereon and, in the case of golf balls, a cover layer of a material comprising gutta percha, balata or the like molded on the rubber-thread winding.

Heretofore it has been proposed to force additional mobile material into the inner envelope by means of a hollow needle after the rubber-thread winding has been applied, to increase the tension of the winding, and it has also been proposed to do the same after the application of the molded cover layer, to put it under tension as well as to increase the tension of the winding, but difficulty has been encountered in preventing escape of the mobile material from the inner envelope through the aperture made therein by the needle. The presence of a substantial volume of pocketed air within the inner envelope also has been a matter of some concern as operating against perfect balance and proper performance of such balls.

The chief objects of my invention are to overcome these several defects and disadvantages, which I do by using a liquid dispersion of rubber, such as natural or artificial latex, which may be preliminarily concentrated to give it a high content of solids, and which may have vulcanizing agents mixed into it, as the mobile substance within the inner envelope, or at least as the substance to be injected into the envelope by means of the needle, and preferably by providing for coagulation of the rubber dispersion at least in the vicinity of the needle aperture, for effectively sealing the aperture.

Suitable apparatus for the practice of my invention is shown in the accompanying drawing, of which

Fig. 1 is a longitudinal section of a ball-holding device and a ball therein.

Fig. 2 is a vertical section of a device adapted for the injection of a rubber-coagulant into the ball, with the holder and ball of Fig. 1 associated therewith.

Fig. 3 is a vertical section of the ball-holding device and ball therein in association with parts of a device similar to that of Fig. 2 but adapted for the injection of a liquid dispersion of rubber into the core of the ball.

Referring to the drawing, the ball-holder comprises a cup-shaped member 10 formed with a breather aperture 11 through its "bottom" wall, a stop-collar 12 secured in proper position on its

exterior by a set-screw 13, a block 14 loosely fitting within the cup-shaped member 10, formed with a conical recess in one end adapted for the reception of the ball, designated 15, and adapted to abut the "bottom" of the cup-shaped member 10 at its other end, and provided centrally of the conical recess with a positioning pin 16 adapted to extend into the rubber windings of a ball impaled upon it as shown, but not to extend so far into the ball as to puncture the flexible wall, 17, of the core of the ball. The flowable material which is in the core at the time the windings are applied thereto is shown at 18, Fig. 2.

For retaining the impaled ball and the loosely-fitting block 14 in the cup-shaped member while the assembly is being manipulated, as in being inserted in and removed from the devices of Figs. 2 and 3, a screw plug 19 formed with spanner holes 20, 20 and with an external stop-flange 21 of less outer diameter than the outer diameter of the cup-shaped member 10 is adapted to be screwed into the end of the member 10 and is formed with a conical recess in its inner face the wall of which is adapted to be engaged by the ball when by the injection of liquid the ball has been enlarged to a determinate size, the block 14 and the plug 19 being determinately spaced with relation to each other by their engagement with the cup-shaped member 10.

The plug 19 is centrally formed with an aperture 22 for the admission of the injecting needle.

The injecting device of Fig. 2 comprises a base 23 formed on its upper side with a well for a fluid 24 such as water supplied to it under pressure through a pipe 25 and an aperture 26 in the floor of the base.

A flexible diaphragm 27 is clamped throughout its margin between the base and a magazine member 28 held to the base by bolts 29, 29 and formed, over the diaphragm, with a chamber for a body of rubber-coagulant 30. This chamber is in communication with the bore of a hypodermic needle 31 mounted in a nipple 32 screwed upon a projection formed on the member 28, the needle being in position to punch through the wall of the ball to the interior of the core when the holder of Fig. 1 with the ball therein is forced down into a guide member 33 screwed onto a boss formed on the member 28, the point of the needle being just within the interior of the core when the stop-collar 12 on the holder abuts the top of the guide member 33, as shown in Fig. 2, and the weight of the ball and of the block 14 being supported by the frictional engagement of the

material of the ball with the injection needle, the ball as shown in Fig. 2 being not yet expanded by injection and consequently being out of contact with the conical face of the plug 19.

5 The member 28 is provided with a filler aperture adapted to be closed by a screw 34, for the introduction of the rubber-coagulant 30 into the chamber, and an aperture adapted to be closed by a screw 35 is provided in the base member 23 for venting air from the chamber therein as the water 24 is initially conducted into the chamber, to avoid the poorly-controlled squirting effect that would result from the presence of an entrapped elastic substance such as air.

10 15 The apparatus which is partially shown in Fig. 3 is the same as that shown in Fig. 2 except that the magazine chamber is filled with a liquid dispersion of rubber, 36, instead of the coagulant 30 of Fig. 2.

20 In the practice of my method with the apparatus illustrated the ball, comprising the envelope containing the flowable material 18, which may be any of the substances usually employed for that purpose or may be a concentrated natural latex or other dispersion of rubber, and may be loaded with a weighting material, is mounted in the holding devices as shown in Fig. 1 and the assembly is then forced down in the guide member 33 of Fig. 2 until the parts are in the 25 relative positions there shown, with the point of the injection needle just within, or almost within, the interior of the core.

30 Some of the coagulant 30 may then be injected into the interior of the core, so that the 35 flowable substance already therein, or the mixture, is given coagulating properties, or the coagulant may be injected only into the aperture which is formed by the needle in the material of the wall of the core or in the rubber of the 40 windings, or both, by maintaining the pressure on the coagulant, through the diaphragm 27,

while the needle is being withdrawn from the ball by removing the holder assembly from the guide member 33.

5 The holder assembly is then transferred to the apparatus of Fig. 3 and similar procedure is employed for injecting into the core, through the same needle-hole, a sufficient amount of the rubber dispersion 36 to distend the ball to such size as is permitted, with a given pressure upon the dispersion, by the space defined by the block 10 14 and plug 19.

10 The holder assembly is then removed from the injection device, the plug 19 is removed from the member 10, whereupon the block 14 and ball are dropped out of the member 10 and the ball, 15 then readily grasped, is removed from the block 14 and its pin 16.

15 As the needle hole substantially closes by reason of the resilience of the material as the ball is withdrawn from the injection device of Fig. 2 substantially none of the coagulant or of the flowable material originally in the core escapes in the small time required for mounting the holder assembly in the injecting device of Fig. 3, and as it is withdrawn from the latter the presence of the coagulant within the ball causes such coagulation of the rubber of the dispersion as permanently to seal the needle hole.

20 I claim:

25 The method of making a ball which comprises winding rubber thread under tension upon a liquid filled envelope constituting a core, thereafter applying a coagulant internally of the structure 30 35 in the vicinity of the wall of the core, and then injecting a liquid dispersion of rubber into the core and effecting coagulation thereof in the vicinity of the injection aperture in the wall of the core by reason of the presence of the said coagulant.

35 CHARLES W. LEGUILLOON. 40
